Application January 17, 1945, Serial No. 573,290

4 Claims. (Cl. 160—84)

1

This invention relates to a foldable closure for door and partition use.

One chief object of this invention is to provide a closure of the character indicated and of a materially less number of parts than that required by comparable closures.

Another chief object of this invention is to provide in such a closure, which may be covered upon opposite sides, a crossed hinge framework and devoid of lazy tongs and like levers.

A further object of this invention is to provide an improved connection between such hinge framework and the covering material.

Still a further object of this arrangement is to provide, in association with an overhead supporting trackway, a trolley connector between the closure proper and trackway whereby the closure interchangeably may be utilized with a so-called concealed or exposed trackway.

Other objects and features of the invention will be set forth more fully hereinafter.

The full nature of the invention will be understood from the accompanying drawing and the following description and claims.

In the drawings:

Fig. 1 is a side elevational view of a single closure for an opening provided with an overhead trackway of exposed type, the closure being shown in closing position, parts being broken away, and some parts being shown in section, the covering material being omitted for clearness.

Fig. 2 is a top plan view of such a closure, in the same relative position, the trolley connections being omitted.

Fig. 3 is a view similar to Fig. 2 and of the same parts, the entire closure being shown in collapsed position.

Fig. 4 is a vertical sectional view of the selectively connectible lead post trolley and associated trackway and lead post.

Fig. 5 is a perspective view of an intermediate trolley yoke.

Fig. 6 is a transverse sectional view of a trackway and intermediate trolley and yoke.

Fig. 7 is a perspective view of the lead post trolley connecting yoke.

Fig. 8 is a transverse sectional view of the same, the associated trolley and trackway, the connector being shown in elevation.

Fig. 9 is a vertical sectional view of a hinge plate, the cover, and the connection therebetween.

In certain of the figures, 10 indicates a so-called exposed channel overhead track with inwardly directed lower flanges 11 forming groove

2

12. In other figures, 110 indicates a similar channel of the concealed type. By this is meant the track is nested in a groove and the groove or slot 112 is exposed.

The track, in either case supports a lead post trolley A, see Figs. 1, 4 and 8, and one or more intermediate trolleys B, see Figs. 1 and 6. These are connected to the closure proper as herein-after specified. The rear post may have a slot seated projection C, see Fig. 1, to insure proper positioning of the rear post D.

This rear post includes vertical channel 13 to which is secured the clip connector 14, detachably associated with a clip socket 15 secured to one sidewall 16 of the opening to be closed by the closure.

The opposite wall 17 mounts a grooved member 18 that engages clip member 19 carrying cushion contact member 20, these being carried by tube 21, same comprising the lead post.

The covering comprises an outer layer 22 and a reenforcing layer 23 or layers 23 and 82, see Figs. 2, 3 and 9. The adjacent ends of the two opposite side coverings are lapped at the posts and suitably secured thereto between members 13 and 14 and members 21 and 19.

The lead post mounts on opposite sides handles 24, see Figs. 2 and 3, and nested in said lead post is the lock structure 25, see Fig. 1, having key operable member 26, actuator 27 associated with bolt 28 that projects from the lead post into a notch 29 forming lock 30 in the member 18. This bolt is released by elevating same, etc., whereupon the closure can be opened and then collapsed, as shown in Fig. 3.

In Fig. 1 the closure is shown comprised of an upper series of comparatively wide plates G, a lower series H and one or more intermediate series I, all lower series being of strap type, that is not as wide as series G. The covering may be secured to each series or solely to the upper series as shown at J in Fig. 1 and in detail in Fig. 9.

Herein each series of full length hinge plates terminates at each end in a pair of half length hinge plates. The end supports for each series includes a U-shaped strap 31 suitably secured to the adjacent post at 32 and having two parallel apertured portions 33 for mounting pintle 34. The length of strap 31 is approximately equal to the depth of the hinge series to be accommodated thereby.

Herein, see Figs. 1 and 8, the strap 31 has stock taken therefrom at 35 to provide tongue 36 provided with vertically aligned apertures 37. In Fig. 4 a slightly different type strap is illustrated.

It includes base 131, extended at 136 and apertured at 137. This base has formed thereon one or more ears 133 for pintle 134.

The lead post trolley includes two axially aligned wheels 38, as shown in Figs. 4 and 8, carried by axle 39, in turn mounted in yoke member 40. This member has the elongated extension 41 for track slot guidance. Depending therefrom is connecting portion 42 provided with a pair of parallel bores or anchoring seats 43 to selectively receive pivot pin or anchor 44 mounted in the lead post at 45 and the strap at 37 or 137.

Yoke 40 includes notch 46 so that when the track is of exposed type, the trailing edge of the lead post can nest therein. When the track is of so-called concealed type this accommodation is unnecessary. From the aforesaid, it will be noted the yoke swivels on the horizontal axis of pin 44 and on the axis of shaft 39. Hence, a universal joint results for limited movement. The projection 41, however, limits such movement on pin 44 to track slot width.

Also, the wheel and axle construction is such that rolling contact is had on flanges 11 or 111, while side play of the wheels is limited and rolling wheel side contact is also had. Also, the tread width of the wheels equals that of flange width, notwithstanding the axle mounting of the wheel having a thickness substantially that of the tread width of the wheel. This is obtained by the offsetting, as it were, in said wheels and the recessing at 47 of member 40 for wheel hub accommodation.

Reference will now be had to Figs. 1, 5 and 6. Herein the intermediate trolley is illustrated. It includes wheels 38, axle 39, yoke 48 recessed at 49 for wheel hub nesting and the depending connector portion 50.

Same includes transverse slot 51 and central bore 52 countersunk at 53 for pintle head 54 accommodation. Access is had thereto by slot 55 to pass pintle body 56. This pintle is elongated over other central pivots to be referred to and is headed as shown, see Fig. 6.

In Fig. 1 the upper series of hinge plates comprise half length plates 59, rib reenforced as at 60, and having longitudinally aligned and spaced butts 61, the butts of the plates being alternated in alignment as shown and receiving pintle 34. The latter is peripherally grooved as at 62 to seat a split retainer ring 63, two adjacent butts being spaced apart for such accommodation.

These half hinges at each end of the series diverge and, see Figs. 2 and 3, terminate in spaced butts 64 seating pintles 65. A pair of crossed full length hinge plates 66, see Fig. 1, are notched as at 67 at their midportions, and the central stock is curled or semi-curved at 68 for central pintle 56 or the like reception. Such pintle is similarly grooved as at 62 to seat the split locking ring 63 if desired. These butts or partial butts are alternated from the slot or notch associated plates, which are rib reenforced as at 69. The half length plates are biased at 70, while the full length plates have the central biased portions 71.

When extended the half plates interengage or lock at 72, see Fig. 2, and thus limit the extensible movement. When collapsed the offsetting 71 throws the plates together so the folds X are uniform and regular in the covering and same will not crack.

Herein, see Fig. 1, two lower and narrower width strap series are provided. Except for width, the several plates of series I and H hinges

are similar to the upper series G hinge plates.

Whenever full length pintles are employed and stops are desired to prevent possible sag, friction locking washers 80, see Fig. 8, may also be employed below hinges, etc.

Reference will now be had to Fig. 9 wherein the covering 22 includes reenforcing fabric 23 stitched thereto as at 81, which also secures a second fabric strip 82. Each hinge and half hinge is suitably apertured at 83.

The connector J, see Figs. 1 and 9, includes prong 84, normally constrained to the dotted line position. Said prong includes transverse portion 85 seatable in aperture 83 and connecting to co-planer scroll portion 86, which terminates in projection 87 provided with lateral hook 88.

Portion 85, as well as the prong, is passed through webbing or anchor strip 82 at 89, while hook 88 overhangs the upper edge of the hinge plate. When so mounted the prong 84 is positioned as shown in full lines, so that the connector is under tension and frictionally locked to the hinge plate, but may be forcibly detached therefrom.

25 Note also strip 82, by being interposed between the clip and the hinge, silences such contact. Also strip 23 prevents wear of covering 22 upon the clip.

Figs. 4, 6 and 8 illustrate portions of a closure structure applied to an exposed and a concealed track. In the latter instance the top of the articulated mechanism is spaced at a greater distance from the track than in the former (exposed track) instance. The cover material shown in Fig. 9 is extended upwardly and top hemmed to just clear the flanges 11 in Fig. 6 and the same type of top hem is provided to clear the flanges 111 in Fig. 8. Hence the depth of this hem may be varied in accordance with the spacing between the track (or ceiling) and articulated mechanism.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. In a foldable closure for an opening having track means therein, lead and rear posts and trolley means for track means engagement, the combination of at least one series of interlaced collapsible and extensible strap type hinge plates connecting said posts, said series comprising a pair of diverging half length hinges connected to an end post, and a plurality of centrally notched full length hinge plates pivotally connected end to end and centrally, the end ones of the last mentioned plates being connected to the half hinges, the interlaced, slotted hinged plates having lateral interfitting nestable association, the pivotal connections between the crossed plates including pintle nesting portions in alignment, at least one adjacent pair of such portions being spaced apart, the pintle when nested having a peripheral groove coincident with and exposed by that spacing, and groove seated pintle embracing means.

2. In a foldable closure including an extensible and collapsible series of hinge plates and

a foldable covering for same, the combination of a fabric strip secured to the covering, and clip means pressing the strip to the adjacent plate and passing through said strip and plate and overhanging both and hooking upon the latter for securing the covering to the plate.

3. In a foldable closure as defined by claim 2 wherein there is provided an intermediate fabric strip between the covering and strip for covering protection from the clip means.

4. In a foldable closure for an opening having track means therein, lead and rear posts and trolley means for track means engagement, the combination of at least one series of interlaced collapsible and extensible strap type hinge plates connecting said posts, said series comprising a pair of diverging half length hinges connected to an end post, and a plurality of centrally notched full length hinge plates pivotally connected end to end and centrally, the end ones of the last mentioned plates being connected to the half hinges, the interlaced, slotted hinged plates having lateral interfitting nestable as-

5

sociation, the trolley means comprising track engaging means and a member depending therefrom, said member having a plurality of anchoring seats disposed parallel to the track and each other, and an anchor selectively connecting said member to the post at either of the seats for track-plate immediate proximity association.
